CLAIM

We claim the ornamental design for a container with three door lid, as shown and described.

DESCRIPTION

FIG. 1 is a front top right side perspective view of our new container with a three door lid;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front elevation view of the container with the three door lid of FIG. 1 with the lid main door shown open 90 degrees;

FIG. 9 is a rear elevation view thereof;

FIG. 10 is a right elevation view thereof;

FIG. 11 is a top plan view thereof;

FIG. 12 is a front elevation view of FIG. 1 with two side lid doors shown open 90 degrees;

FIG. 13 is a rear elevation view thereof;

FIG. 14 is a right elevation view thereof;

FIG. 15 is a left elevation view thereof;

FIG. 16 is a top plan view thereof; and,

FIG. 17 is a front elevation view of a second embodiment of a container with three door lid. FIG. 17 depicts a symbolic break in the container with three door lid and any portion of the article between the break lines forms no part of the claimed design.

The broken lines in the drawings showing the container with three door lid illustrate the portions of the container with three door lid that form no part of the claimed design.
